UNITED STATES PATENT OFFICE.

LEE DE FOREST, OF NEW YORK, N. Y., ASSIGNOR, BY MESNE ASSIGNMENTS, TO DE FOREST
RADIO TELEPHONE CO., A CORPORATION OF NEW YORK.

WIRELESS TELEGRAPHY.

No. 926,933.

Specification of Letters Patent.

Patented July 6, 1909.

Application filed March 22, 1905. Serial No. 251,365.

To all whom it may concern:

Be it known that I, LEE DE FOREST, a citizen of the United States of America, and a resident of the city of New York, State of New York, have invented certain new and useful Improvements in Wireless Telegraphy, the principles of which are set forth in the following specification and accompanying drawings, which disclose the form of the invention which I now consider to be the best of the various forms in which the principles of the invention may be embodied.

This invention relates to spark-gaps for transmitting-apparatus in wireless or spark telegraphy, and more particularly to that type of spark-producing apparatus which involves the use of the vapor of a metal, such as mercury, as in a vacuum spark-gap tube. In this type the mercury is employed in its usual form, as a liquid, and its spark is called a mercury vapor spark, although other liquids may be employed.

The invention consists in improvements in the construction, form and relative arrangement of the parts of the apparatus, whereby it is rendered more durable and less liable to self-destruction and more convenient for use in wireless telegraphy. Certain of the improvements are the result of the discovery made by me, that with the constructions disclosed herein, the changes are less apt to follow along one streak in the vacuum along the glass of which the device is composed, so that the discharges are less apt to heat and break the glass and thus entirely destroy the device.

Of the drawings, Figure 1 is a vertical longitudinal section of a device embodying my improvements; Fig. 2 is a similar view of a device embodying certain of the improvements shown in Fig. 1; and Fig. 3 is a similar view of a device embodying certain of the improvements shown in Fig. 1.

As is shown in Fig. 1, E is a spark-gap vacuum tube, preferably composed of glass. The vapor condensing chamber K forms the upper extremity of the tube, and is constructed with a depending annular portion F, which forms an annular receptacle for the liquid M, such as mercury, which is the liquid preferably employed. This annular receptacle F is laterally disposed, in that it is disposed entirely around the tube. The depending part of the condenser chamber K, 55 may not, however, extend entirely around

the tube to form an annular receptacle. The tube as thus constructed is adapted to be used in a substantially vertical, or nearly vertical, position, and when so used, the liquid will be retained in the receptacle F, as 60 will be readily understood. The expression "substantially vertical," herein employed, means not tipped so great a degree toward the horizontal plane as to render the device 65 inoperative.

It is obvious that the device may be tipped a considerable degree, but it is equally obvious that it is inoperative, as to some of its features, when used in a horizontal position, or in a position tending toward an inversion. The lower end of the tube forms the receptacle I for the liquid M, which is operatively retained therein when the tube is used in a substantially vertical position.

A terminal A of metal, such as platinum, 70 is sealed into the lower glass wall of the receptacle F, its upper end extending inside the wall of the receptacle and in electrical contact with the liquid M. Another terminal D is sealed into the glass wall of the receptacle I, and its upper end extends inside the wall and in electrical contact with the liquid M in the bottom of the tube, i. e., in the receptacle I. These two terminals A and D may be connected to the electrical circuits 75 of a wireless telegraphy sending station, in any of the ways known to those skilled in the art; so that when the signaling key closes the circuit, the vapor spark will pass between the liquid electrodes M in the receptacles F 80 and I. I have found that when the device is constructed as described, so as to be capable of use in a substantially vertical position, the vapor discharge is much less likely 85 to follow in a streak along the inside wall of the glass tube. The result is that, in the described construction, there is much less chance of the tube being destroyed by the heating and consequent breaking of the glass, 90 as in cases where the walls of the space between any two liquid electrodes might be horizontal.

Between the condensing chamber K and the bottom receptacle I, are formed the laterally disposed liquid receptacles G and H, which comprise depending portions 95 adapted to receive the liquid M, and to retain the same when the tube is used in a substantially vertical position; the liquid receptacle I being arranged to operatively re- 100 105 110

tain the liquid only when the tube E is in a substantially vertical position. These receptacles G and H are laterally disposed in the sense that they are formed in the side or 5 sides of the tube E. Into these receptacles G and H are sealed the terminals B and C, in the manner described with respect to the terminals A and D.

All features of construction are to be produced in any of the ways known to those skilled in the art of glass working; and, before sealing the tube, the liquid is to be placed in the receptacles, and a practical vacuum should be produced in the tube by 10 any of the known or suitable methods. The construction which permits the use of a plurality of more than two liquid electrode receptacles is particularly valuable in that it permits the different individual electrodes 15 to be utilized in different pairs, thus allowing the use of a variety of voltages in the different cases when the exigencies of signaling require different electrical pressures.

In Fig. 2 is disclosed a form of the device 20 wherefrom the laterally disposed electrode receptacles G and H are omitted, the construction being otherwise as described with respect to Fig. 1.

In Fig. 3 is disclosed a form of the device 25 wherefrom is omitted the annular receptacle F formed by the depending portion of the condenser chamber K, the construction being otherwise as disclosed in Fig. 1.

I claim:

30 1. A spark gap device for wireless tele-

graph transmitting apparatus including a substantially straight vacuum tube containing a liquid electrode in the bottom end thereof and an enlarged chamber at the upper end thereof into which the tube opens, 40 said enlarged chamber constructed with a depending annular channel surrounding the mouth of the tube, said channel containing a liquid electrode, said tube having laterally disposed offsets intermediate its ends forming depending pockets to receive liquid electrodes, and circuit terminals extending into 45 said liquid electrodes.

2. A spark gap device for wireless telegraph transmitting apparatus, including a 50 substantially straight vacuum tube, containing a liquid electrode at its lower end, and having a plurality of offset depending pockets intermediate its ends, said pockets containing liquid electrodes, and circuit terminals extending into said liquid electrodes. 55

3. A spark gap device for wireless telegraph transmitting apparatus, including a 60 vacuum tube having a condensing chamber at one end and containing a liquid electrode at its other end, said tube, intermediate its ends having laterally offset depending pockets, each containing a liquid electrode, and circuit terminals extending into said liquid electrodes. 65
